(57) CLAIM

The ornamental design for a wreath-shaped cup, as shown and described.

DESCRIPTION

FIG. 1 is front view of a wreath-shaped cup showing my new design;

FIG. 2 is a back view thereof;

FIG. 3 is a side view thereof;

FIG. 4 is a front perspective view thereof;

FIG. 5 is a bottom view thereof; and,

FIG. 6 is a top view thereof.

The broken lines in the drawings depict portions of the wreath-shaped cup that form no part of the claimed design.
